DESIGN FOR A GLOVE

Benjamin Ginsberg, New York, N. Y.

Application November 13, 1940, Serial No. 96,535

Term of patent 7 years

To all whom it may concern:

Be it known that I, Benjamin Ginsberg, a citizen of the United States and resident of New York city, in the county of New York and State of New York, have invented a new, original, and ornamental Design for a Glove, of which the following is a specification, reference being had to the accompanying drawing, forming a part thereof.

Fig. 1 is an inside plan view of a glove, showing my new design.

Fig. 2 is an outside plan view of the same.

I claim:

The ornamental design for a glove, as shown.

BENJAMIN GINSBERG.
